UNITED STATES PATENT OFFICE.

VICTOR GUINZBURG, OF NEW YORK, N. Y., ASSIGNOR TO I. B. KLEINERT RUBBER COMPANY, OF NEW YORK, N. Y., A CORPORATION OF NEW YORK.

ELASTIC FABRIC.

Application filed June 4, 1920. Serial No. 386,564.

To all whom it may concern:

Be it known that I, VICTOR GUINZBURG, a citizen of the United States, and a resident of the city, county, and State of New York, have invented a certain and useful Improvement in Elastic Fabrics, of which the following is a specification.

This invention relates to an elastic fabric which is composed of a combination of elastic and inelastic materials and which is adapted for use in connection with articles of wearing apparel. The object of this invention is to provide an elastic or expandable fabric which can be economically made; which will be light in weight and which will possess a maximum amount of elasticity.

A further object of this invention is to provide an elastic fabric which will be particularly adapted for use in connection with articles of wearing apparel, more especially such articles as hose supporters, belts, waistbands for garments and many other articles.

With these objects and other objects which may hereinafter appear in view, I have devised the particular arrangement of parts hereinafter set forth and more particularly pointed out in the claim appended hereto.

Reference is to be had to the accompanying drawing, forming a part hereof, in which—

Figure 1 is a front view of a strip of elastic fabric made in accordance with my invention;

Figure 2 is a rear elevation of the same;

Figure 3 is a sectional view of the line 3—3 of Figure 1, looking in the direction of the arrows.

Throughout the various views of the drawings similar reference characters designate similar parts.

In the preferred embodiment of my invention, as disclosed in the accompanying drawing, 1 indicates a section of material which is preferably in the nature of an inelastic textile material, such as muslin, silk or the like. This strip or section 1 is gathered or shirred throughout its length and thus forms a plurality of folds or shirrings 2.

Secured to one face of the section of inelastic material 1 and at the edges thereof, are two strips of an elastic material 3. These strips are preferably in the nature of nar-

row, flat elastic webbing and are secured to the inelastic fabric 1 by means of a form 55 of overstitching such as is disclosed at 4.

It will be noted that the form of stitching disclosed as at 4 performs two functions, one of which is to enclose the elastic strip 3 and secure it to the strip 1 and the other 60 being to provide an "edging" for the inelastic strip 1 to prevent it from fraying or unraveling. Thus the necessity for hem-stitching the edges of the strip 1 is avoided 65 as the reinforcing of the edges of the inelastic strip 1 and the attachment of the elastic strip 3 thereto is performed by the one operation of sewing the stitches 4 in position.

The use of the stitches 4 in place of hem-stitched edges results in considerable saving of material due to the fact that the turning-in of the material to produce the hemmed edges is not necessary.

Intermediate of the elastic strips 3 but on 75 the opposite side of the inelastic strip 1 is a flat, unshirred strip of elastic 5, which is secured in place by means of the line of stitching 6. It will thus be seen that the edge strips of elastic are situated on one 80 side of the inelastic strip while the central elastic strip is placed on the opposite side. All of the strips may however, be placed on one side and the arrangement of the strips may be varied without departing 85 from the spirit of my invention.

The strips 3 may be spaced apart as desired or as many of these strips may be used as may be necessary according to the width of the fabric to be produced.

It will also be noted that the elastic strips 3 are unshirred and that the inelastic fabric situated between these strips is provided with sufficient fullness to permit the strip of material thus produced to have a slight 95 lateral expansion and to conform to the body of the wearer under all conditions.

The shirrings or folds 2 in the inelastic material permit the inelastic material to move with the elastic strips when said strips are stretched and the entire piece of fabric thus possesses elasticity within the limits of stretch or expansion of the shirrings or folds produced in the inelastic material 1.

From the foregoing, it is obvious that my invention is not to be restricted to the exact

embodiment shown but is broad enough to cover all structures coming within the scope of the annexed claim.

Having described my invention, what I

5 claim is:—

An article of the class described, comprising a strip of gathered or Shirred textile fabric having a plurality of spaced narrow strips of elastic secured to it by stitching, 10 some of said strips being secured on one face of the fabric and a strip on the oppo-

site face thereof, two of said strips constituting flat, unshirred elastic strips at the opposite longitudinal edges of said fabric strip, and over-stitching enclosing said edge 15 strips to secure the same to one face of the fabric strip and to provide a reinforcement for the edges of said fabric strip.

Signed at the city, county and State of New York this 2nd day of June, 1920.

VICTOR GUINZBURG.
